UNITED STATES PATENT OFFICE.

OTTO FLOHR, OF BUFFALO, NEW YORK, ASSIGNOR TO CHARLES A. POOLEY
OF SAME PLACE.

CAR-COUPING.

SPECIFICATION forming part of Letters Patent No. 445,242, dated January 27, 1891.

Application filed April 7, 1890. Serial No. 346,868. (No model.)

To all whom it may concern:

Be it known that I, OTTO FLOHR, a citizen of the United States, residing in Buffalo, in the county of Erie and State of New York, 5 have invented certain new and useful Improvements in Car-Couplers, of which the following is a specification.

This invention relates, generally, to car-couplers of the class having a horizontally-10 swinging coupling-jaw pivoted to the draw-head and a horizontally-swinging locking-pawl for locking the jaw, both these members being constructed to move in one direction by gravity when released, and it relates particu-15 larly to couplers for locomotive-tenders and to means whereby such couplers can be conveniently operated by the engineer of the locomotive to which the tender is attached.

My invention aims to provide certain im-20 provements in car-couplers of this general class and to provide an improved tender-coupler, and has for its object to provide means whereby the coupler can be operated with more facility than heretofore, means 25 whereby dust and other foreign matter can be excluded from the working parts of the coupler to a greater extent than previously, to improve the construction of the coupling-jaw, and also to provide a coupler for locomotive-tenders which shall have all the advan-30 tages of automatic couplers of the general class described and be capable of engagement with car-couplers generally.

To this end in carrying out my invention 35 I provide a dust-cover for closing the aperture provided for receiving the operating-chain of the coupler, and I construct the coupling-arm of the coupling-jaw with a solid inner or working face, forming an unbroken 40 wall from the top to the bottom of the arm, and in applying my improvements to locomotive-tenders I extend the operating-chain from the coupler along the tender and into reach of the engineer, and I construct on the 45 buffer-beam of the tender a coupler of improved form and embodying the automatic features and horizontally-swinging coupling-jaw of car-couplers of the class described.

In the accompanying drawings, which illus-50 trate my invention, Figure 1 is a fragmentary side elevation of a locomotive and tender,

showing my improvements applied to the latter. Fig. 2 is a fragmentary plan of a car-coupler provided with my improvements and attached to the buffer-beam of a tender. Fig. 55 3 is a horizontal section thereof, and Fig. 4 is a vertical section thereof cut on the line 4 4 in Fig. 2.

Referring to the drawings, let A represent the locomotive; B, the tender thereof; C, the 60 car-coupler for the tender; D, the coupling-jaw; E, the locking-pawl therefor, and F the operating-chain for moving the pawl.

The tender B is constructed with the usual buffer-beam B', to which the coupler C is 65 fastened. The coupler C consists of an inclosing casing within which the swinging coupling-jaw D and a lock therefor (such as E) are pivoted, the casing being constructed with top wall a and bottom wall b and with 70 side walls c and d, and terminating at its inner side with a vertical rear base-plate e, adapted to be bolted to the buffer-beam B' of the tender. The walls a b c d are preferably of the shape usually employed in couplers of 75 this class, adapted for ordinary cars, and are cast in one piece with the rear base-plate e. The latter preferably projects beyond the side walls sufficiently to permit the passage through it of bolts f f, by means of which it 80 is secured to the buffer-beam B' of the tender. Flanges g g are preferably provided between the side walls c and d and the projecting ends of the base-plate e for the purpose of increasing the strength of the coupler. The top and 85 bottom walls a and b may be suitably ribbed, if desired, as shown in Fig. 2.

The coupling-jaw D is constructed, as usual, with the coupling-arm h and the locking-arm i, and is mounted on inclines j in such manner that it has a normal tendency to swing to the uncoupled position. The arm i is constructed to be engaged when in the coupled position by a lock—such, for example, as the locking-pawl E—and when in the uncoupled 95 position to swing outwardly, as seen in Fig. 3.

The pawl E is pivoted within the casing C and constructed to swing between two inclines k and l within the casing, so constructed that the pawl will have a normal 100 tendency to swing into the locked position.

The chain F is secured to the pawl E and

passes out through a hole *m* in the top of the casing. The chain preferably extends from the coupler forward along the tender and terminates near the forward end thereof and 5 within the reach of the engineer of a locomotive to which the tender may be attached, whereby by operating the chain the engineer can control the coupler without leaving his position in the locomotive-cab. Preferably 10 the chain *F* passes upwardly into a pipe *n*, near the top of the tender and extending longitudinally thereof, and terminates at the forward end of the pipe in a handle *o*, as shown in Fig. 1; or the chain may be carried over 15 the tender and to the cab of the locomotive, as shown in dotted lines in Fig. 1.

In order to prevent the entrance of dust through the hole *m*, I provide a cover or stopper *p* over this hole. The cover *p* is preferably 10 fixed to the chain *F* above the casing, and is so constructed that when the pawl *E* is in the locked position the cover *p* will cover the hole *m*, and when the chain *F* is pulled to uncouple the coupler the cover *p* will be 15 moved away from the hole *m* until the chain *F* is released, whereupon it will again seat itself over the hole and close the latter.

As heretofore constructed the coupling-jaw *D* has had a horizontal notch extending transversely across its coupling-arm *h* and adapted 20 to receive an ordinary coupling-link *G*, which was retained therein by a coupling-pin *H*, which passed through the usual pin-hole *q* near the end of the arm *h*. This construction was disadvantageous in that the edges of 25 the notch on the inner face of the arm *h* were liable to catch the corners of an adjacent coupling-jaw when the couplers were in use, and the bifurcated end of the coupling-jaw 30 presented an uneven working-face for contact with the corresponding jaw of an adjacent coupler. According to my invention I construct the arm *h* of the coupling-jaw of a greater width than heretofore, and with a recess *r* in its upper end for receiving the ordinary coupling-link *G*, and I close said recess 35 at the back by a wall *s* on the inner face of the arm *h*, whereby the inner face presents an uninterrupted contact-surface for engagement with the jaw of an adjacent car-coupler.

In operating my improved car-coupler when applied to tenders, the engineer, when desiring to uncouple the coupler, will pull the chain up, thereby swinging the locking-pawl *E* out 45 of engagement with the coupling-jaw *D* and permitting the latter to swing to the uncoupled position. Upon releasing the chain *F* the pawl *E* will return to the locked position and the cover *p* will seat itself over the hole *m*, 50 thereby closing the latter. As the jaw *D* is swung to the coupled position by coupling with an adjacent coupler, its locking-arm *i* will swing back the pawl *E* until it has passed the latter, whereupon the pawl will swing into 55 engagement with the arm *i* and lock the jaw in the coupled position.

My invention provides an improved coupler

for locomotive-tenders which is capable of coupling with car-couplers generally, and which combine strength and simplicity of parts, and can be automatically operated without the necessity of stepping between the cars to effect the coupling operation.

My improved dust-cover *p*, and also my improved coupling-jaw *D*, can be applied generally to car-couplers of the class having a horizontally-swinging coupling-jaw and a movable lock for securing the jaw in the coupled position.

My invention may be modified as to details of construction, and certain of its features may be used independently of others without departing from the nature of the invention.

What I claim is the following defined novel features and combinations, substantially as hereinbefore set forth, viz.:

1. In a car-coupler for locomotive-tenders, the combination, with the tender and a car-coupler secured thereto and consisting of a swinging coupling-jaw constructed to have a normal tendency to swing to the uncoupled position and a swinging pawl for locking said jaw in the coupled position, of a connection secured at one end to said pawl and adapted when pulled to move the latter and release said jaw, said connection extending from said pawl forward along the tender and terminating near the forward end thereof and within the reach of the engineer of a locomotive to which the tender may be attached, whereby by operating said connection the engineer can control said coupler without leaving his position.

2. In a car-coupler, the combination, with a swinging coupling-jaw and a swinging pawl for holding the latter in the coupled position, and an inclosing casing or draw-head within which said jaw and pawl are pivoted, said casing being constructed with a hole in its upper part, of a connection secured at one end within said casing to said pawl and extending thence through the hole in the top of said casing and adapted when pulled to operate said pawl, and a cover or stopper secured to said connection and constructed when said pawl is in the locked position to cover the hole in said casing, whereby when the coupling is in the locked position the entrance of dust within said casing through said hole is prevented by said cover.

3. In a car-coupler for locomotive-tenders, the tender and a car-coupler secured thereto, said coupler consisting of a swinging coupling-jaw constructed to have a normal tendency to swing to the uncoupled position and a swinging locking-pawl for locking said jaw in the coupled position, in combination with a chain secured at one end to said pawl and adapted when pulled to move the latter and release said jaw, said chain extending from said pawl forward along the tender, guided by suitable guides, and terminating near the forward end of the tender in a handle within the reach of the engineer of the locomotive to which the

tender may be attached, substantially as set forth.

4. In a car-coupler for locomotive-tenders, the tender and a car-coupler secured thereto, 5 said coupler consisting of a swinging coupling-jaw and a swinging locking-pawl for locking said jaw in the coupled position, in combination with a guide tube or pipe secured to and extending along the tender from 10 a point above the coupling to a point at the forward end of the tender, and a chain secured at one end to said pawl and extending

therefrom through said guide-tube and terminating outside of the front end of said guide-tube in an operating-handle, substantially as set forth. 15

In witness whereof I have hereunto signed my name in the presence of two subscribing witnesses.

OTTO FLOHR.
